UNITED STATES PATENT OFFICE.

JAMES A. HEALEY, OF WAKEFIELD, MASSACHUSETTS, ASSIGNOR TO PARKER BROTHERS, INCORPORATED, OF PORTLAND, MAINE, A CORPORATION OF MAINE.

GAME APPARATUS.

1,102,986.

Specification of Letters Patent.

Patented July 7, 1914.

Application filed April 2, 1914. Serial No. 829,146.

To all whom it may concern:

Be it known that I, JAMES A. HEALEY, a citizen of the United States, and a resident of Wakefield, in the county of Middlesex and State of Massachusetts, have invented an Improvement in Game Apparatus, of which the following description, in connection with the accompanying drawings, is a specification, like characters on the drawings 10 representing like parts.

This application relates to game apparatus and particularly to game apparatus of that type wherein one or more articles are adapted to be propelled, projected or cast 15 toward or into sockets or receptacles.

In order that the principle of the invention may be readily understood, I shall describe a single embodiment thereof in the accompanying drawing, wherein—

20 Figure 1 is a plan view of the board or base forming a part of the game apparatus and of one of the devices adapted to be propelled or projected toward the receiving sockets or portions thereof; Fig. 2 is a side elevation of said board or base; Fig. 3 is a vertical longitudinal section thereof; Fig. 4 is a side elevation of one form of propelling or projecting implement or device which may be used in playing the same; and Fig. 25 30 5 is a side elevation of one form of connected units preferably used in practising the game.

Referring more particularly to the drawing, I have in Figs. 1, 2 and 3 represented 35 one form of base or board preferably used in playing the game. The said base or board may be of any suitable shape, but is preferably of elongated rectangular form. I have herein represented it as composed of a 40 bottom 1 which may be of wood, paper fiber or any other suitable material. It is, however, preferably perfectly smooth, so that the devices or units employed in playing the game may be rolled therealong. The bottom 1 is 45 provided with surrounding walls 2—2, 3—3 preferably of wood suitably secured at the corners and preferably longitudinally grooved for the reception of the edges of the bottom 1. At or adjacent the end the 50 more remote from the player I provide a number of receptacles or sockets 4, 5 and 6. These may be formed in any suitable manner, but preferably the bottom 1 is recessed at this point and is there provided with a

cloth or felt layer 7 having therein the said 55 sockets. The material beneath the felt may also be socketed if desired. Preferably the said sockets or receptacles are arranged in rows or series, the value thereof being indicated by figures painted or otherwise formed 60 upon the cloth, felt or other layers 7. The said sockets are, in the preferred embodiment of the game, so spaced apart as to receive the peculiarly constructed connected units which are propelled or projected to 65 toward the same, as will be hereinafter more fully set forth. Preferably I provide a guard rail 8 at the more remote or head end of the board, and if desired a cross member 9 at the nearer or foot end of the board. 70 In playing the game, it is preferred to maintain the base of the board at an inclination. For that purpose I preferably provide a hinged bail or wire 10 which, when the game is packed for storage or shipment, may 75 be fitted flat against the under side of the base. Each member to be propelled, projected or cast simultaneously into a plurality of receptacles or sockets is composed of a plurality of connected units, one form 80 whereof is represented in Figs. 1 and 5. I have therein shown the said member as consisting of two substantially spherical pieces or rolls 11, 12 spaced apart and connected by a bar or rigid member 13, the length of said 85 bar 13 being substantially equal to the distance apart of adjacent sockets in any one of the rows or sockets 4, 5 and 6. Within the scope of my invention, the units 11, 12 may be of any other shape than spherical 90 and they may be connected otherwise than as shown, as for example by a flexible piece. While I have shown merely two units connected together in suitable manner, it is evident that any greater number than two may 95 be connected together, as for example three or more.

Preferably the construction is such that the units may be rolled along the bottom 1 toward and into the sockets 4, 5 and 6, but 100 obviously and within the scope of the invention the said units may be propelled, projected or cast in any suitable manner and may be even tossed thereinto. Interest is, however, added to the game by rolling the 105 devices along the bottom piece 1. For that purpose the hand of the player may be used, but preferably I employ an implement 14,

having a bent or handle portion 15 and a head 16 by which the connected units may be struck a blow mid length of the uniting bar 13.

5 It will be evident that very considerable skill and dexterity are required to strike a propelling blow to the uniting bar 13 at such a point and in such a manner and with just sufficient force that the connected units 10 will be rolled evenly along the base 1, so as to enter neighboring sockets. Within the scope of my invention any suitable arrangement of the sockets may be made and if desired the sockets of adjacent rows or series 15 may be spaced a proper distance to permit two connected units simultaneously to enter sockets thereof. Preferably, however, the spacing of the sockets is such that the connected units or devices must be propelled 20 evenly along the bottom 1 and into the said sockets.

The felt or cloth layer 7 being preferably rougher than the bottom 1, substantially retards the movement of the connected units.

25 Any suitable number of connected units may be employed, and obviously the game is adapted to be played by any number of persons.

If desired and within the scope of the invention I may employ a plurality of sizes or lengths of the united units adapted respectively to fit sets of receptacles or sockets spaced apart distances corresponding to said different sizes or lengths. For example, by 35 providing units 11, 12 connected together by different lengths of uniting bars 13, each set of united units will be adapted for reception only in those sockets spaced a corresponding distance apart.

40 Having thus described one illustrative embodiment of my invention, I desire it to be understood that although specific terms are employed, they are used in a generic and descriptive sense and not for purposes of limitation, the scope of the invention being set forth in the following claims:

1. A game apparatus consisting of a base having a plurality of sockets or receptacles, and a plurality of connected units adapted 50 to be propelled or projected thereinto.

2. A game apparatus consisting of a base having a plurality of sockets or receptacles, and a plurality of connected rolling units adapted to be propelled or projected thereinto.

55 3. A game apparatus consisting of a base having a plurality of sockets or receptacles, and a pair of substantially spherical, con-

nected members adapted to be propelled or projected thereinto.

60 4. A game apparatus consisting of a base having a plurality of sockets or receptacles, and a pair of spaced or connected, substantially spherical members adapted to be propelled or projected thereinto.

65 5. A game apparatus consisting of a base having a plurality of receptacles or sockets and a pair of spherical members rigidly connected by a spacing bar and adapted to be propelled or projected into said sockets 70 or receptacles.

75 6. A game apparatus consisting of a base member having a plurality of sockets or receptacles spaced sufficiently to permit the reception of connected units, and a plurality of connected units adapted to be propelled or projected thereinto.

80 7. A game apparatus consisting of a pair of spaced, connected units, and a base member having a plurality of sockets, pairs of which are spaced a distance equaling that of said units.

85 8. A game apparatus consisting of a pair of spaced, rigidly connected units, and a base member having at a portion relatively remote from the player, a plurality of sockets, pairs of which are spaced a distance equaling that of said units.

90 9. A game apparatus consisting of a base having a plurality of sockets or receptacles, a plurality of connected units adapted to be propelled thereinto, and a propelling implement or device.

95 10. A game apparatus consisting of a base having a plurality of receptacles or sockets, a pair of rigidly connected rolling units adapted to be propelled thereinto, and a propelling implement for striking a propelling blow to said connected units.

100 11. A game apparatus consisting of a base having a plurality of receptacles or sockets, a pair of rigidly connected rolling units adapted to be propelled thereinto, and a propelling implement for striking a propelling blow to said connected units, said rolling units being spaced apart a distance equal to that existing between certain of said receptacles or sockets.

110 In testimony whereof, I have signed my name to this specification, in the presence of two subscribing witnesses.

JAMES A. HEALEY.
